UNITED STATES PATENT OFFICE.

ALLAN TAWLKS, OF HARVEY, NORTH DAKOTA, ASSIGNOR OF ONE-HALF TO IRA D. CLARK, OF HARVEY, NORTH DAKOTA.

CAR-COUPLING.

No. 921,482.

Specification of Letters Patent.

Patented May 11, 1909.

Application filed November 7, 1908. Serial No. 461,527.

To all whom it may concern:

Be it known that I, ALLAN TAWLKS, a citizen of the United States, residing at Harvey, in the county of Wells and State of North Dakota, have invented a new and useful Car-Coupling, of which the following is a specification.

The invention relates to improvements in car couplings.

10 The object of the present invention is to improve the construction of car couplings, more especially the means for connecting the draw bar with the draft rigging, and to provide a simple, inexpensive and efficient construction of great strength and durability, designed for use in connection with various types of draft rigging, and capable of enabling the draw bar to be readily disconnected and removed when desired for replacing a 20 broken spring or for any other purpose.

A further object of the invention is to provide a car coupling, adapted particularly for use on freight cars, and capable of being disconnected and detached from the draft rigging without removing the follower plates, the spring or springs and the draft frame or iron, which connects the draw bar with the draft rigging.

With these and other objects in view, the 30 invention consists in the construction and novel combination of parts hereinafter fully described, illustrated in the accompanying drawing, and pointed out in the claims hereto appended; it being understood that various 35 changes in the form, proportion, size and minor details of construction, within the scope of the claims, may be resorted to without departing from the spirit or sacrificing any of the advantages of the invention.

40 In the drawings:—Figure 1 is a side elevation of a car coupling, constructed in accordance with this invention, and shown applied to a fragment of a car, the latter being in section. Fig. 2 is a horizontal sectional view of 45 the same. Fig. 3 is a vertical longitudinal sectional view on the line 3—3 of Fig. 2. Fig. 4 is a transverse sectional view on the line 4—4 of Fig. 2. Fig. 5 is a detail sectional view, illustrating the manner of retaining the draw bar from the draft yoke.

Like numerals of reference designate corresponding parts in all the figures of the drawing.

1 designates a draw bar, provided with a 55 squared front portion adapted to present a

flat lower face to a carry iron 2, as clearly illustrated in Fig. 1 of the drawing. The front end of the draw bar may be equipped with a draw head 3 and coupler mechanism of any preferred construction, and the rear portion 4 of the draw bar is rounded and is provided at its rear end with an integral oblong head 5, arranged in a vertical position, as illustrated in Figs. 1 and 3 of the drawing, when the draw head is in its normal horizontal position. The head 5 of the draw bar is detachably interlocked with a draft iron or yoke 6, composed of spaced upper and lower sides and a connecting vertical rear portion 7, preferably formed integral with the sides. 60 The front or outer terminals of the sides are provided with vertical lugs 8, located at the inner opposite faces of the upper and lower sides and arranged vertically to form a contracted entrance to the draft iron or yoke. 65 The space between the lugs 8 is of a width to receive the rounded rear portion 4 of the draw bar, and the head 5 of the draw bar is adapted to fit against and engage the inner vertical faces of the lugs, as clearly shown in 70 Figs. 1 and 3 of the drawing, whereby the draw bar is securely connected with the draft yoke or iron. The draft yoke or iron receives the follower plates 9 and 10 and the spring 11 of the draft rigging. Only a single 75 draft or cushioning spring is illustrated in the accompanying drawing, but any type of draft rigging having one or more springs may be employed, as will be readily understood.

The front and rear faces or edges of the 80 head 5 are vertical, the rear faces being arranged to bear against the follower plate 9. The upper and lower ends 12 of the head are rounded, and the upper and lower sides 6 of the draft yoke are provided at their inner 85 faces with longitudinal grooves 13, forming ways and presenting curved faces arcuate in cross section and forming ways to receive the rounded ends of the head 5 and adapted to permit the head to slide longitudinally 90 and also to be rotated laterally to arrange it in the horizontal position, illustrated in Fig. 5 of the drawing. When the head is arranged in a horizontal position, it is adapted to pass through the space or passage between 95 the projecting lugs at the front or outer end of the draft yoke or iron. This operation may be performed without removing the follower plates and does not necessitate the taking down of the draw guides 14 and other 100 105 110

portions of the draft rigging. In event of
breakage of a spring, or should it become
necessary to remove the draw bar for any
other purpose, the draw bar may be quickly
5 detached by simply rotating it horizontally
one quarter of a revolution and drawing it
outward. It may then be entirely removed
from the car or left supported by the carry
iron. It is also desirable to connect the
10 front or outer portions of the sides of the
draft iron or frame, and it will also be neces-
sary to loosen or remove such connecting
means. Various forms of connections may
be employed. In the accompanying draw-
15 ing I have illustrated a U-shaped bolt or
member 15, composed of vertical sides and a
connecting top portion 16, the lower terminals
of the sides being threaded for the re-
ception of nuts, which secure a transverse
20 plate 17 against the lower side of the draft
yoke or iron. The upper side of the draft
yoke or iron is preferably provided with a
groove 18 to form a seat for the connecting
portion of the U-shaped bolt or fastening
25 member, and the lower side is provided with
a corresponding recess 19 for the reception of
the connecting plate 17. The connecting
means prevents any relative lateral separa-
tion or spreading of the engaging portions of
30 the sides of the draft iron or yoke.

When the parts are assembled, the draw
bar is adapted to reciprocate freely in the
draw iron or yoke and is cushioned by the
spring in the usual manner.

Having thus fully described my invention, 35
what I claim as new and desire to secure by
Letters Patent, is:—

1. The combination of a draft yoke includ-
ing spaced sides having a contracted en-
trance and provided in rear of the latter 40
with ways, and a draw bar arranged to re-
ciprocate in the contracted entrance and pro-
vided with a head arranged to pass through
the contracted entrance when the draw bar
is turned from its normal position and adapt- 45
ed to engage the yoke when the draw bar is
in its normal position, said head being recip-
rocatable in the ways of the yoke.

2. The combination of a draw yoke includ-
ing spaced sides provided with inwardly ex-
tending lugs spaced apart and forming a con-
tracted entrance, said sides being also pro-
vided with guide-ways extending rearwardly
from the lugs, a draw bar reciprocatable 50
longitudinally of the yoke and having a head
slidable in the said guide-ways and inter-
locked with the lugs through rotary move-
ment, and a detachable fastening device con-
necting the front portions of the sides to pre- 55
vent the same from spreading.

In testimony, that I claim the foregoing as
my own, I have hereto affixed my signature
in the presence of two witnesses.

ALLAN TAWLKS.
